OTHER PUBLICATIONS

Russian Official Action (w/English translation) dated May 11, 2011 for Application No. 2010503597, filed Sep. 12, 2010. The translated Official Action is relied upon as a statement of relevance regarding the AU registration.

Primary Examiner — Prabhakar Deshmukh*(74) Attorney, Agent, or Firm* — Nixon & Vanderhye, P.C.(57) **CLAIM**

The ornamental design for an electronic computer stand, as shown and described.

DESCRIPTION

FIG. 1 is a front, right and bottom perspective view of an electronic computer stand showing our new design;
FIG. 2 is a rear, left and top perspective view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a left side elevational view thereof;
FIG. 8 is a right side elevational view thereof;
FIG. 9 is a perspective view thereof, shown in alternate position with an open and close portion shown in an open position; and,
FIG. 10 is a perspective view thereof, shown the article in its environmental use.
The broken lines environment is for illustrative purpose only and forms no part of the claimed design.
